UNITED STATES PATENT OFFICE.

EDMUND LOMAX CRIDGE, OF PASSAIC, NEW JERSEY.

AUTOMATIC BRAKE FOR RAILWAY-VEHICLES.

SPECIFICATION forming part of Letters Patent No. 740,246, dated September 29, 1903.

Application filed November 4, 1902. Serial No. 130,056. (No model.)

To all whom it may concern:

Be it known that I, EDMUND LOMAX CRIDGE, a citizen of the United States, and a resident of Passaic, in the county of Passaic and State of New Jersey, have invented a new and Improved Automatic Brake for Railway-Vehicles, of which the following is a full, clear, and exact description.

My invention relates to an automatic brake for railway-vehicles, a more particular object being to devise means for automatically venting the air-brake of a locomotive, thereby causing the mechanical brakes to be applied in case the engineer disregards a semaphore-signal.

I will describe an automatic brake for railway-vehicles embodying my invention and then point out the novel features in the appended claims.

Reference is to be had to the accompanying drawings, forming a part of this specification, in which similar characters of reference indicate corresponding parts in all the figures.

Figure 1 is a fragmentary front elevation showing my invention as applied to a locomotive. Fig. 2 is a central section, somewhat enlarged, showing the valve mechanism. Fig. 3 is a somewhat similar view taken at right angles to Fig. 2. Fig. 4 is a horizontal section upon the line 4-4 of Fig. 3 looking in the direction of the arrow. Fig. 5 is a horizontal section upon the line 5-5 of Fig. 3 looking in the direction of the arrow.

Upon a post 1, stationed at a point adjacent to the railway-track, is a movable semaphore-arm 2, connected with the post by means of a pivot 3. A pitman 4 is connected with the semaphore-arm for moving the same into different relative positions indicating, respectively, "safety" and "danger." A boss 5 is mounted upon the semaphore-arm for the purpose of tripping the valve mechanism hereinafter described. A series of levers 6, which may be actuated by the aid of any mechanical device, is provided for the purpose of setting the semaphore-arm 2 into its different predetermined positions by means of the pitman 4.

Upon a locomotive 7 is mounted a pipe 8, to be connected with a train-pipe or with some analogous pipe connected with the air-brake in such manner that when the pipe 8 is

vented the brakes are applied. This much of the mechanism being old, no description of it appears to be necessary.

A casing 9 communicates with the pipe 8 and is made in two portions screwed together at 10, as indicated in Figs. 2 and 3. The upper portion is provided with a web 10, preferably integral therewith, this web being provided with a conical opening 11, constituting a valve-seat. Another web, 12, at the bottom of the upper portion of the casing, is provided with passages 13^a. The base of the lower portion of the casing 9 is provided with passages 14, as indicated more particularly in Figs. 2 and 3.

A longitudinal plunger 15 is slidably mounted within the web 12 and is provided with channels 13 and with a frusto-conical head 16, constituting a valve which fits the valve-seat 11. The lower portion of the plunger 15 is provided with a collar 17, which is engaged by a spiral spring 18. This spring also engages the web 12, so as to normally draw the plunger downward. The lower portion of the plunger 15 is likewise provided with a groove 18^a of the shape indicated in Figs. 2 and 3.

A pin 19, provided with a handle 20, is slidably mounted in the lower portion of the casing 9 and is provided with a head 21, which engages the groove 18^a. A spiral spring 22 surrounds this pin, as indicated in Fig. 3, and normally tends to force the head 21 into the groove 18^a. Upon the extreme lower end of the casing are mounted the bearing-lugs 23, supporting the pivot 24, upon which is mounted a lever 25, provided with cam-lobes 26 and so arranged that the tripping of the lever, as indicated in Fig. 3, causes one of the lobes 26 to elevate the plunger 15.

A drip-valve 27 is provided with a thumb-piece 28 for the purpose of removing any moisture which may lodge within the casing.

The operation of my device is as follows: When the semaphore-arm is placed in the position indicated in Fig. 1, the boss 5 partially obstructs the path of the lever 25 and the forward motion of the engine causes the lever 25 to encounter the boss, being tripped thereby, as indicated in Fig. 3. This causes the elevation of the plunger 15 and lifts the valve 16 from its seat 11, thereby allowing

the air from the pipe 8 to escape around the valve 16 and through the channels 13, making its exit through the passages 13^a and 14, thus applying the brakes. The tension of 5 the spring 22 causes the head 21 of the pin 19 to enter the groove 18^a, thereby maintaining the plunger in its uppermost position and holding the valve open, so that the train cannot proceed until the handle 20 is withdrawn, 10 so as to allow the valve 16 to engage its seat. The idea is that the engineer should heed the semaphore-signal; but if it should happen that he does not do so the train will be automatically stopped and cannot proceed until 15 the handle 20 is adjusted, which of course implies that the trainmen must have notice of the condition of the signal before the train can proceed. The spring 18 is not necessary in all instances, but is desirable for the reason 20 that it presses the valve firmly upon its seat and keeps the same closed regardless of the air-pressure. When the arm 2 is raised, indicating "safety," the lever 25 cannot be brought into engagement with the boss 5.

25 It will be noted that the semaphore-arm engages directly with the trip-lever 25, so that no intermediate mechanism is necessary. The setting of the semaphore-arm is *per se* the setting of the automatic brake mechanism.

Having thus described my invention, I claim as new and desire to secure by Letters Patent—

1. An automatic brake for railway-vehicles, 35 comprising a hollow casing mounted upon a locomotive and connected with the train-pipe thereof, said hollow casing being provided with a valve-seat, a movable valve mounted within said hollow casing and free to engage 40 said seat, a cam-lever mounted upon said hollow casing and provided with a lobe engaging said movable valve, locking mechanism for temporarily maintaining said valve out of contact with said seat, and means disposed 45 adjacent to the railway-track for automatically tripping said lever.

2. An automatic brake for railway-vehicles, 50 comprising a hollow casing mounted upon a locomotive and connected with the train-pipe thereof, said casing being provided with a valve-seat, a longitudinal plunger mounted

within said casing and free to slide in the general direction of its length, said plunger being provided with a valve engaging said seat, a lever for actuating said plunger in the 55 general direction of its length, thereby raising said valve from said seat, mechanism disposed adjacent to the track for automatically tripping said lever, a spring-pin for temporarily holding the plunger in the position it assumes when said lever is tripped, and means, 60 controllable at will, for adjusting said spring-pin.

3. An automatic brake for railway-vehicles, 65 comprising a hollow casing mounted upon a locomotive and connected with the train-pipe thereof, said casing being provided with a valve-seat, a plunger mounted within said casing and provided with a valve engaging said seat, and a cam-lever provided with a 70 lobe engaging said plunger.

4. An automatic brake for railway-vehicles, 75 comprising a hollow casing mounted upon a locomotive and connected with the train-pipe thereof, said casing being provided with a valve-seat, a plunger mounted within said casing and provided with a valve engaging said seat, a cam-lever provided with a lobe 80 engaging said plunger, and means for normally pressing said valve-seat into a certain position, thereby closing said valve and maintaining said lever in position to engage a stationary pin.

5. An automatic brake for railway-vehicles, 85 comprising a hollow casing mounted upon a locomotive and connected with the train-pipe thereof, said casing being provided with a valve-seat, a plunger mounted within said casing and provided with a valve engaging said seat, a cam-lever provided with a lobe 90 directly engaging said plunger, and a movable semaphore-arm disposed adjacent to the railway-track and provided with a portion adapted for use as a signal and with a boss 95 for tripping said lever.

In testimony whereof I have signed my name to this specification in the presence of two subscribing witnesses.

EDMUND LOMAX CRIDGE.
